(57) **CLAIM**

The ornamental design for a “semiconductor wafer processing tape,” as shown and described.

DESCRIPTION

FIG. 1 is a perspective view showing our new design;
FIG. 2 is a top plan view;
FIG. 3 is a bottom plan view;
FIG. 4 is a left side view;
FIG. 5 is a front side view;
FIG. 6 is a right side view;
FIG. 7 is a cross sectional view at 7—7 of FIG. 1; and,
FIG. 8 is a cross sectional view at 8—8 of FIG. 1.
